M. N. LUDLOW

HOLDER FOR PISTOLS OR REVOLVERS

Filed March 31, 1924

Inventor
Margery N. Ludlow

UNITED STATES PATENT OFFICE.

MARGERY N. LUDLOW, OF ALTADENA, CALIFORNIA.

HOLDER FOR PISTOLS OR REVOLVERS.

Application filed March 31, 1924. Serial No. 703,274.

To all whom it may concern:

Be it known that I, MARGERY N. LUDLOW, a citizen of the United States, residing at Altadena, in the county of Los Angeles, 5 State of California, have invented a new and useful Holder for Pistols or Revolvers, of which the following is a specification.

This invention relates to a holder, the purpose of which is to enable a revolver or pistol to be held ready for instant use, to protect a person, for example in an attempted robbery or "hold-up". The general object of the invention is to provide a device for this purpose which is of very simple construction and which can be very readily attached in an inconspicuous place, to a support. The holder may be secured within an automobile and within convenient reach of the driver, or it may be mounted in a convenient position in a desk in a bank or in an office where money or valuables are handled. A further object of the invention is to provide a device of this kind which can be readily constructed from a short rod or wire; 25 also to provide a construction which will enable the device to be made from a blank of very simple form, which blank can be constructed from a short rod or wire. A further object of the invention is to construct the device so that the weight of the pistol or revolver assists in retaining it on the holder.

Further objects of the invention will appear hereinafter.

35 The invention consists in the novel parts and combination of parts to be described hereinafter, all of which contribute to produce an efficient holder for pistol or revolver.

40 A preferred embodiment of the invention is described in the following specification, while the broad scope of the invention is pointed out in the appended claims.

In the drawing:

45 Figure 1 is a fragmentary side elevation and partial section showing part of an automobile and illustrating the holder attached to the instrument-board and supporting a revolver.

50 Fig. 2 is a vertical section taken through the edge of a desk and illustrating the device supporting a revolver and attached beneath the desk top.

Fig. 3 is a side elevation of a preferred

embodiment of the device upon an enlarged 55 scale.

Fig. 3^a is a plan of the tip of the device illustrated in Figure 3.

Fig. 4 is a front elevation of the holder 60 illustrated in Figure 3.

Fig. 5 is a cross section on the line 5—5 of Figure 3 but showing the barrel of the revolver mounted on the holder.

Fig. 6 is a plan of a blank which may be 65 used in constructing the holder.

In its general construction the holder comprises a projecting stem adapted to be received within the barrel of the pistol or revolver, and having a keeper which is constructed so that it resiliently engages a side 70 of the pistol, pressing the same against the stem; this pressure is a yielding pressure so that if sufficient force is exerted upon the pistol it can be instantly drawn out of the holder.

75 In a preferred embodiment of the holder the stem 1 is constructed so that it extends transversely from the plane of a foot or base-plate 2, said foot being preferably integral with the stem and provided with holes 3 to receive screws to fasten the holder in place. In addition to the stem 1, the plate 2 supports a keeper 4 which has a part or extension 5 lying near the side of the stem 1 and preferably extending substantially parallel 80 with it. The keeper 4 may be also formed integrally with the plate 2 and is divided into two forks 4^a and 4^b.

85 In practice, I prefer to construct the holder from a short bar of metal such as wire of large diameter. In order to do this I produce a blank 6 having the features of construction illustrated in Figure 6. In order to form this blank I flatten the rod or bar near its middle portion to form the plate 7 which will eventually constitute the foot or base-plate 2. I then form a longitudinal slit or slot 8 in one end of the bar. I

90 form holes 9 for the screws in the plate 7 and I then bend the blank up to give it the form illustrated in Figures 3 and 4; however, before doing this, I spread the split end of the bar so as to form the two forks 4^a and 4^b and I swage the ends of the forks 95 to form the extensions 5 so that they present concave faces 10 toward the stem 1 and convex faces on their outer sides.

100 After the holder has been bent into this

shape, I treat it by the well known "baked-rubber process" by means of which I deposit and vulcanize on the holder a layer or covering 11 of baked rubber. This covering protects the holder from corrosion and also protects the rifling of the pistol barrel, preventing it from coming in direct contact with the metal of the holder.

In constructing the keeper 4, it is desirable 10 to have the extensions 5 located slightly below the stem 1. My object in doing this is to utilize the weight of the pistol or revolver to increase the clamping effect of the extensions 5. This effect is clearly illustrated in 15 Figure 5, an inspection of which will show that as the stem 1 is deflected slightly downwardly by the weight of the barrel, the barrel wedges itself in between the concave faces 10 of the extensions. 20 Furthermore, in order to facilitate the placing of the pistol in position, I prefer to form the extreme tips of the extensions 5 with inclined or outwardly curved faces 12 (see Figure 3^a), the effect of which is to produce two throats or angles 13 on each side; as the tip of the stem 1 projects slightly beyond the extremities of the extensions 5, it will be evident that if the muzzle of the pistol is slipped over the stem 1 it will engage 25 the faces or cheeks 12 and shove the resilient forks 4^a and 4^b apart so as to permit the gun barrel to slide into position. The extensions 5 may be of any desired length, but I prefer to make them sufficiently long to engage 30 with the magazine 14 of a revolver, such as the revolver 15 illustrated in Figures 1 and 2.

In Figure 1 the holder is represented attached to the face of the instrument-board 40 16 of an automobile, so that the stem 1 inclines upwardly. It is not necessary that the stem 1 project exactly at right angles to the plate 2, but it is desirable that it should incline upwardly towards its tip at a sufficient angle to insure that the pistol will 45 not tend to fall off.

If desired, the holder may be attached at a 50 convenient point on a desk. In this case, I prefer to attach the foot plate to an angle bracket 17, secured on an inner side wall 18 of the desk and at a short distance below the desk top 19.

If desired, the holder may be mounted by 55 attaching the foot-plate 2 on the floor of the automobile in a convenient place near the driver.

The holder operates to support a pistol or 60 revolver in such a way that it will be held motionless and at the same time it can be drawn for instant use by simply seizing the handle of the revolver and pulling it backwards.

It is understood that the embodiment of

the invention described herein is only one of the many embodiments this invention may take, and I do not wish to be limited in the practice of the invention, nor in the claims, to the particular embodiment set forth.

In practice, where it is desired to have the holder maintain its proper adjustment indefinitely, I prefer to construct it of a good quality of steel or similar resilient metal.

What I claim is:—

1. A holder for a pistol or revolver, having a foot constructed to be attached to a support, having a straight stem extending from the foot transversely to the plane of the foot of a diameter to be received within the barrel of the pistol, and operating to pass into the barrel of the pistol, and a keeper arranged parallel with said stem and engaging the pistol and pressing the same against the stem.

2. A holder for a pistol or revolver, having a foot constructed to be attached to a support, having a straight stem extending from the foot transversely to the plane of the foot of a diameter to be received within the barrel of the pistol, and operating to pass into the barrel of the pistol, and a keeper having two extensions lying substantially parallel with the stem and constructed of resilient material, said extensions operating to press the side of the pistol and hold the same yieldingly on the stem.

3. A holder for a pistol or revolver having a foot in the form of a plate adapted to be attached to a support, said plate having a substantially straight integral stem projecting therefrom at one end of the plate and of a diameter to be received within the barrel of the pistol, and a keeper in the form of a bar integrally connected with the other end of the plate and having two forks extending substantially parallel with the stem, said keeper being resilient so that said forks operate to press the side of the pistol toward the stem and hold the same yieldingly on the stem.

4. A holder for a pistol or revolver having a substantially straight projecting stem constructed to engage and support the barrel of the pistol and operating to pass into the pistol barrel, and a keeper having a pair of forks with substantially straight extensions operating to engage the pistol on each side to retain the same on the stem, said keeper being resilient and said extensions being located slightly below the stem whereby the weight of the pistol tends to wedge it down between the extensions and increase the holding effect of the keeper.

Signed at Los Angeles, California, this 24th day of March, 1924.

MARGERY N. LUDLOW.
